UNITED STATES PATENT OFFICE.

ALFRED SHEDLOCK, OF JERSEY CITY, NEW JERSEY, ASSIGNOR, BY MESNE ASSIGNMENTS, TO THE AMERICAN TOBACCO COMPANY, OF NEW YORK, N. Y., A CORPORATION OF NEW JERSEY.

BANDING-MACHINE.

No. 840,022.

Specification of Letters Patent.

Patented Jan. 1, 1907.

Application filed September 10, 1902. Serial No. 122,779.

To all whom it may concern:

Be it known that I, ALFRED SHEDLOCK, a citizen of the United States, residing at Jersey City, county of Hudson, and State of New Jersey, have invented certain new and useful Improvements in Banding-Machines, fully described and represented in the following specification and the accompanying drawings, forming a part of the same.

This invention relates to certain improvements in machines for applying bands to articles, the machine being more especially intended for applying ornamental and distinguishing bands to cigars.

The ornamental and distinguishing bands now commonly used in many brands of cigars are usually applied to the cigars by hand, the strip from which the band is formed being folded around the cigar and the ends of the strip being caused to adhere by gum. This hand operation is slow, and, furthermore, the bands thus applied frequently adhere to the cigar, either because there is an excess of gum on the strip or because the gummed portion of the strip comes in contact with the wrapper of the cigar. The cigar or wrapper is therefore liable to be torn when the band is removed, as it usually is before the cigar is smoked.

It is one of the objects of this invention to produce an improved machine by which bands may be rapidly applied to cigars.

A further object of the invention is to produce a machine in which bands may be rapidly applied to cigars, the bands being snugly fitted to the cigars, and at the same time the danger that they will adhere to the cigar-wrappers being obviated.

With these and other objects in view the invention consists in certain constructions and in certain parts, improvements, and combinations, as will be hereinafter fully described and then specifically pointed out in the claims hereunto appended.

In the accompanying drawings, Figure 1 is a front elevation of a machine for applying bands to cigars. Fig. 2 is a rear elevation of the same. Fig. 3 is a side elevation partly in section. Figs. 4, 5, 6, 7, 8, and 9 are detail views illustrating the operation of the band-carrier and applying device.

Referring to the drawings, which illustrate a concrete embodiment of the invention, the

frame, which may be of any desired configuration, is shown as consisting of a front standard 1 and a rear standard 2, said standards being supported on a base 3.

The machine is provided with a suitable holder for the cigars or other articles to be banded. This holder, in the preferred form of the construction, will be arranged to support a plurality of articles and will be given a step-by-step movement to present the cigars to the band-applying device. In the construction shown this holder consists of a ring 4, which is provided with a series of concave recesses 5, in which the cigars are placed by hand or in any other suitable manner, the cigars being retained in the recesses, in the construction shown, by means of springs 6. The holder may be supported and operated in any suitable manner. As shown, it is carried on a disk 7, said disk being loosely mounted on a shaft 8, which is supported in suitable bearings in the standards 1 and 2, before referred to.

The means for giving the holder an intermittent movement may be varied within wide limits. As shown, the interior of the ring 4 is provided with an internal gear 9, the teeth of said gear being in mesh with a pinion 10, mounted on a stud 11, suitably supported in the base 3. This pinion 10 has a broad face and is also in engagement with a mutilated gear 12, which is fixed on the shaft 8. The shaft 8 may be continuously driven in any suitable manner; but such means are not shown, as they are not necessary for an understanding of the invention.

In the preferred form of the construction the bands will be formed before they are applied to the cigars, and the machine will therefore, preferably, embody a former for this purpose. The construction of the former may be varied within wide limits. Preferably, however, the former will be of the collapsible type, and, as shown, there is provided a sleeve 13, which is secured by means of a set-screw 14 in a recess in the frame 2. This sleeve is provided (see Figs. 4 and 5) with a projection or spur 15, to which is secured one end of a flexible metallic strip 16, the other end of this strip being secured to an arm 17, mounted on a shaft 18, said shaft being provided on its rear end with an arm 19, by which the shaft may be rocked.

It is apparent that by rocking the shaft the arm 17 will be moved toward and away from the projection 15, and the former is correspondingly increased or diminished in size.

- 5 The former is shown as distended in Fig. 4 and collapsed in Fig. 5.

The means for rocking the shaft may be of any desired description. Preferably, however, the arm 19 carries a pin 20, which engages with a recess in the arm 21 of a bell-crank lever 21 22, the arm 22 of said lever being provided with a bowl 23, which runs on the periphery of a cam 24, mounted on the shaft 8.

- 15 In operating the machine the operator places the strip from which the band is to be formed around the former when the same is distended, the ends of the strip being united by gum applied thereto in the usual manner.
  - 20 The former is then collapsed, after which the band can be readily removed. While the former might, in some forms of machine in which certain features of the invention might be embodied, be of such a diameter
  - 25 that the band made thereon would be of the same diameter as the cigar to which it is to be applied, in the preferred form of the construction the former will be of a somewhat greater diameter than the cigar, so that the band
  - 30 formed thereon will loosely surround the cigar when it is first positioned thereon. The purpose of this construction will be explained later.

35 The means by which the band is transferred from the former to the cigar may be widely varied in construction. Preferably, however, this transferring means or band-carrier will not only transfer the band to and position it on the cigar, but will snugly apply it thereto. To this end, as shown, the band-carrier includes a pair of straining and creasing jaws, said jaws being operated to take the band from the former and position it on the cigar, they being thereafter further oper-

- 45 ated to strain the band about the cigar and crease it, the surplus material in the band being thus squeezed together and formed into a projection or tab which can be seized and torn away from the band when the band is to
50 be removed from the cigar. When the band-applying jaws are employed, they may be mounted and operated in any desired manner. In the construction shown there is provided a carriage consisting of a block 25,
55 which is arranged to slide on rods 26, which are supported in the uprights 1 and 2. This block or carriage 25 has a depending stud on which is mounted a cam-roller 27, running in a cam-groove 28, formed in a cylinder 29,
60 mounted on the shaft 8, before referred to, said cam serving to give the carriage its reciprocating movement. Loosely mounted in the block 25 is a stem 30, which has a perforated head 31, to which the straining-jaws
65 32 33 are pivoted. These jaws will corre-

spond in shape to the contour of the article to be banded. As shown, inasmuch as the article to be banded is a cigar, these jaws are substantially semicircular in shape.

When the jaws are used to apply a previously-formed band which is larger in diameter than the cigar, they will preferably be constructed not only to strain the band to the cigar but to squeeze and crease the surplus portion of the band so that it is formed into a projection or tab. To this end the jaws will be constructed so that their forward ends meet, and preferably, also, these meeting faces will be arranged to bend the projection or tab which they form from the surplus material of the band at an angle to the diameter of the cigar. In the construction shown this is effected by forming the meeting face of the jaw 33 at an acute angle and the meeting face of the jaw 32 at an obtuse angle, as clearly shown in Figs. 4 to 9.

The means for operating the band-applying device so far described may be of any suitable description. Preferably, however, the applying device as a whole will be moved upward or toward the center of the cigar, so as to bring the band in close contact with the under side of the same, after which the jaws will be moved inward to strain the band and, when the jaws are creasing-jaws, to crease it. In the construction shown an eccentric-rod 35 passes through the perforation in the head 31, the rotation of this rod serving to give the head its vertical movement or movement toward the center of the cigar. Lying alongside the eccentric-rod 35 are two other eccentric-rods 36 and 37. The rod 36 is embraced by an eccentric-strap 38, the eccentric-rod 39 of this strap being pivoted to a boss 40, which extends from the jaw 32. Similarly the rod 37 is embraced by an eccentric-strap 41, the eccentric-rod 42 of which is pivoted to a boss 43, extending from the jaw 33.

The driving means for the eccentric-rods 110 35 and 36 may be of any desired character. As shown, the rod 35 (see Fig. 3 and dotted lines in Fig. 1) is provided with a pinion 44, which is in mesh with a rack formed on one of the arms 45 of a bell-crank lever 45 46, the arm 46 carrying a bowl 47, which is engaged by a cam-groove on the end of the cylinder 29, before referred to. The rod 36 (see Fig. 2) is provided with a pinion 48, which is in engagement with a rack formed on the arm 115 49 of a bell-crank lever 49 50, the arm 50 being provided with a cam-roll 51, which engages a cam-groove formed in the rear end of the cylinder 29. The rod 36 is further provided with a segment-lever 52, said lever 120 125 being in mesh with another segment-lever 53, which is secured to the rod 37. The cams referred to are timed so as to give the rods, through the operating connections described, the movements referred to in the 130 135

proper sequence in order to first move the head 31 up against the cigar and then move the jaws inward in order to strain the band around the cigar. After the band has been applied to the cigar the jaws and head are operated to release the cigar, after which the carriage 25 is moved backward by its cam. The eccentric-rods 36 37 are then operated to cause the jaws to seize or grip the band which has been formed by the operator on the former, the former being collapsed at this time through the mechanism which has been described. After the jaws have gripped the band the carriage is reciprocated in the opposite direction, the jaws being thus caused to carry the band over the cigar into proper position to be strained thereabout and suitably creased. After the jaws have placed the band upon the cigar and creased it so as to form a projecting tab, which is indicated at 56 in Fig. 9, the tab will preferably be bent over so as to lie flat against the band. This may be accomplished by any suitable form of mechanism. As shown, however, there is provided a bending-ring 54, which lies alongside the path of the holder, this bending-ring being located so as to wipe down the projecting tab as the cigars are carried along by the holder.

While the mechanism which has just been described constitutes a preferred embodiment of the invention, it will be understood that the invention may be embodied in mechanism which differs widely from that shown and described. It follows, therefore, that many changes and variations may be made in the construction without departing from the invention. It is also to be understood that certain features of the construction may be used independently of other features and that such use is contemplated. While, furthermore, the machine in which the invention is shown as embodied is particularly intended for placing bands on cigars, it will be understood that mechanisms which fall within the invention may be employed for placing bands on other articles.

What is claimed is—

1. In a cigar-banding machine, the combination with cigar-supporting means, of means for applying bands singly to successive cigars, substantially as described.
2. In a cigar-banding machine, the combination with a holder constructed to support a plurality of cigars spaced from each other, of means for applying a band to each of said cigars, substantially as described.
3. In a cigar-banding machine, the combination with a holder constructed to support a plurality of cigars, of band-applying means operating to supply a band for each cigar and means for producing proper relative movements between the holder and the band-applying means to apply bands to successive cigars, substantially as described.

4. In a cigar-banding machine, the combination with a holder for cigars, of means for applying a formed band to a cigar supported in said holder, substantially as described.

5. In a cigar-banding machine, the combination with a holder constructed to support a plurality of cigars, of means for applying a formed band to each cigar, and means for operating the holder, substantially as described.

6. In a cigar-banding machine, the combination with a former, of a holder for cigars, and means for transferring a band from the former to the cigar, substantially as described.

7. In a cigar-banding machine, the combination with a former, of a cigar-holder, a band-carrier, and means for moving the carrier from the former to the cigar in the holder, substantially as described.

8. The combination with a former, of an article-holder, a band-carrier, means for operating the carrier to cause it to grasp a band on the former, and means for operating the carrier to position the band on the article, substantially as described.

9. The combination with an article-holder, of a band-carrier, means for operating the carrier to position the band with respect to the article, and means for operating the carrier to apply the band to the article, substantially as described.

10. The combination with an article-holder, of means for reducing the diameter of a loosely-fitting formed band on an article in the holder, whereby the band is caused to snugly fit the article, substantially as described.

11. The combination with an article-holder, of a band-applying device including movable straining and creasing jaws, and means for operating said jaws, substantially as described.

12. The combination with an article-holder, of a former, a band-carrier having movable jaws, means for causing the carrier to remove a band from the former, and means for thereafter operating the carrier to apply a band to an article, substantially as described.

13. The combination with an article-holder, of a former, a band-carrier having movable creasing and straining jaws, means for operating the carrier to cause it to remove a band from the former, and means for thereafter operating the carrier to strain and crease a band about an article, substantially as described.

14. The combination with an article-holder, of a former, a band-carrier having movable creasing and straining jaws, means for operating the carrier to cause it to remove a band from the former, means for thereafter operating the carrier to strain and crease a band about an article, and means for turning down the projecting portion of the band, substantially as described.

15. The combination with a collapsible former, of a band-carrier, and means for

causing the band-carrier to remove the band from the former, substantially as described.

16. The combination with an article-holder, of a collapsible former, and means for transferring a band from the collapsed former to an article in the holder, substantially as described.

17. The combination with an article-holder, of a collapsible former, a band-carrier having movable applying-jaws, means for causing the carrier to remove a band from the former and means for thereafter operating the applying-jaws to cause them to strain a band about an article in the holder, substantially as described.

18. The combination with an article-holder, of a collapsible former, a band-carrier having movable straining and creasing jaws, means for causing said carrier to remove a band from the former and position it on an article in the holder, and means for operating the jaws to strain the band about the article and crease the same, substantially as described.

19. The combination with an article-holder, of a collapsible former, a band-carrier having movable straining and creasing jaws, means for causing said carrier to remove a band from the former and position it on an article in the holder, means for operating the jaws to strain the band about the article and crease the band, and means for turning down the projecting portion of the band, substantially as described.

20. The combination with a former, of an article-holder, a carriage, band-applying jaws mounted on said carriage, means for reciprocating the carriage between the former and the holder, and means for operating the applying-jaws, substantially as described.

21. The combination with an article-holder, of a former, a carriage, means for reciprocating the carriage between the former and the holder, straining and creasing jaws mounted on the carriage, and means for operating the jaws to strain and crease a band about an article in the holder, substantially as described.

22. The combination with an article-holder, of a former, a carriage, means for reciprocating the carriage between the former and the holder, straining and creasing jaws mounted on the carriage, means for operating the jaws to strain and crease a band about an article in the holder, and means for turning down the projecting portion of the band, substantially as described.

23. The combination with a movable article-holder, of means for applying a band to an article in the holder, said applying means producing a creased projecting portion, and means alongside the path of movement of the support for turning down said projecting portion, substantially as described.

24. The combination with a rotary article-

holder constructed to carry a plurality of articles, of means for applying a band to each article in the holder, said applying means producing a creased projecting portion, and means alongside the path of movement of the support for turning down said projecting portion, substantially as described.

25. The combination with a former, of an article-holder, a carriage, a band-applying device mounted on the carriage said device including movable jaws, means for operating the jaws to cause them to grip a band on the former, means for reciprocating the carriage whereby the band is positioned on an article, means for giving the applying device a movement toward the center of the article, and means for moving the jaws toward each other, substantially as described.

26. The combination with an article-holder, of a collapsible former, a carriage, a band-applying device mounted thereon said device including movable straining and creasing jaws, means for operating the jaws to grip a band on the former, means for reciprocating the carriage to cause the applying device to position a band on the article, means for moving the applying device toward the center of the article, means for operating the jaws to strain and crease the band, and means for thereafter turning down the creased projecting portion of the band, substantially as described.

27. The combination with a rotary article-holder constructed to carry a plurality of articles, of a collapsible former, a carriage, a band-applying device mounted thereon said device including movable straining and creasing jaws, means for operating the jaws to grip a band on the former, means for reciprocating the carriage to cause the applying device to position a band on the article, means for moving the applying device toward the center of the article, means for operating the jaws to strain and crease the band, and means alongside the path of movement of the holder for turning down the creased projecting portion of the band, substantially as described.

28. The combination with an article-holder, of a carriage, a head loosely mounted therein, an eccentric for operating the head, a pair of jaws pivoted thereto, and eccentrics for operating the jaws, substantially as described.

29. The combination with an article-holder, of a former, a carriage, means for reciprocating the carriage between the support and the former, a sliding head loosely mounted in the carriage, an eccentric-rod for operating the head, a pair of jaws pivoted to the head, and a pair of eccentric-rods for operating the jaws, substantially as described.

30. The combination with an article-holder having a plurality of pockets therein, means for giving the holder an intermittent

movement, a collapsible former, a carriage, a reciprocating head mounted in the carriage, a pair of jaws pivoted to the head, eccentric-
5 rods for operating the head and jaws, and means for operating the rods, substantially as described.

31. The combination with an article-holder having a series of pockets, of gearing for giving the same an intermittent rotation, 10 a carriage, supports therefor, a cam for sliding the carriage on the supports, a collapsible former, a band-carrying head loosely mounted in the carriage, an eccentric-rod for mov-

ing the head, a pair of straining and creasing jaws mounted in the head, eccentric-rods for 15 operating the jaws, gearing for operating the eccentric-rods, and a presser-plate located alongside the path of movement of the holder, substantially as described.

In testimony whereof I have hereunto set 20 my hand in the presence of two subscribing witnesses.

ALFRED SHEDLOCK.

Witnesses:

DAVID GRANT,
SYDNEY I. PRESCOTT.
